CHARLES B. PAGE, OF EVANSTON, AND ALBERT C. KALK, OF CHICAGO, ILLINOIS, ASSIGNEES, BY MESNE ASSIGNMENTS, TO THE G. W. DULANY TRUST, OF CHICAGO, ILLINOIS, A COMMON LAW TRUST

WATER HEATER

Application filed November 2, 1928. Serial No. 316,699.

The present invention relates to improvements in water heaters and steam generators, and has particular reference to devices of this kind adapted for use in heating systems for buildings.

In heaters utilizing gaseous or vaporized fuel, some fuel is likely to leak from the burners into the combustion chamber during idle periods, thereby causing danger of explosions when lighting the burners to start up operation. One of the important objects of the present invention therefore resides in the provision in a novel heater utilizing a gaseous or vaporized fuel of means for venting the combustion chamber during idle periods.

Another object of the present invention resides in the provision of a new and improved water heater in which the water is given a rapid circulation so as to improve the efficiency of heat transmission and to accelerate the circulation of the water through the heating system.

A further object resides in the provision in a water heater of a novel arrangement of heating tubes whereby a more nearly uniform velocity of the products of combustion in passing over the tubes is maintained.

Other objects reside in the provision of a new and improved water heater which is efficient in operation, and economical in fuel consumption, in which the water is heated rapidly, which is simple, inexpensive and compact in construction, which is easily assembled and disassembled, and in which a counter flow is provided between the products of combustion and the water.

Further objects and advantages will become apparent as the description proceeds.

In the accompanying drawings, Figure 1 is a horizontal sectional view taken along line 1—1 of Figure 3 of a heater embodying the features of our invention.

Figure 2 is a horizontal sectional view taken along line 2—2 of Figure 3.

Figure 3 is a vertical sectional view taken along line 3—3 of Figure 1.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

Referring more particularly to the drawings, the heating unit shown may be used either as a water heater or a steam generator, but for convenience of description will be designated hereinafter as a water heater.

The water heater may be of any suitable form, and in the preferred embodiment is generally cylindrical in shape and disposed vertically, and comprises a body structure 10 resting on a base 11. The interior of the body structure 10 constitutes a vertical chamber closed at the upper end by a dome 12, and opening at the lower end into the base 11. Of the chamber, the upper end is utilized as a combustion chamber 13, and the lower portion 14 is utilized to enclose heating tubes 15 for the water.

Any desired number of suitable burners may be provided for the combustion chamber 13, and these may be arranged in any suitable manner. In the present instance, eight burners 16 of standard construction mounted in peripherally spaced relation in the side walls of the body structure are provided. While any suitable fuel may be used, preferably the burners 16 are adapted to burn gas, and to this end are connected to a gas line 17 and to an air line 18, leading respectively to suitable sources of gas and compressed air (not shown).

The base 11 may be of any suitable construction, and in the present instance has a

peripheral side wall 19 and top and bottom walls 20 and 21. The top wall 20 has a circular opening 22 communicating with the tube chamber 14, and the marginal portion of the 5 wall about the opening serves to support the body structure 10. A circular upstanding flange 23 concentric with the opening 22 serves to locate and hold the body structure 10 in position. The base 11 is formed with a 10 lateral extension 24 having a stack outlet 25, and the interior thereof constitutes a smoke box or chamber 26 providing a gas outlet from the chamber 14 to the stack.

When gas, particularly commercial gas, is 15 used as fuel, water vapor may condense out of the products of combustion as the latter are cooled to below the evaporation temperature in the course of their passage to the base 11. To drain off this condensate, the 20 bottom wall 21 is inclined, and is provided with a drain opening 27 at its lowermost point.

The body structure 10 is formed with a peripheral or surrounding water chamber 28, 25 annular in the present instance, about the interior, and to this end has inner and outer peripherally spaced walls 29 and 30. The lower end of the water chamber 28 is closed by an end wall 31, and the upper end opens 30 into the interior of the dome 12 which comprises outwardly convex spaced inner and outer walls 32 and 33. The burners 16 are mounted in annular walls 34 opening through the water chamber 28.

35 Preferably, for convenience in construction and in assembly and disassembly, the body structure 10 is formed in closed upper and lower sections 35 and 36, the upper section being formed integral with the dome 12, and 40 the sections being rigidly secured together, as by means of lugs 37 and bolts 38. A plurality of peripherally spaced connections 39 serve to provide free communications between the sections. Preferably, the lower 45 section 36 also is divided into closed semi-cylindrical sections 40 and 41 secured together in any suitable manner, as by means of lugs 42 and bolts 43.

The heating tubes 15 may be of any suitable form and may be arranged in any suitable manner. In the present instance they are disposed in an annular space about a central core 45 which rests on a pedestal 44 on the bottom wall 21 of the base 11 and projects 55 axially into the heating chamber 14, and which preferably is of refractory material. The heating tubes 15 in the preferred form are arranged in four vertical concentric coils 46, 47, 48 and 49, with the tubes of adjacent coils disposed in staggered relation, and each coil comprises two tubes 15 wound in parallel. The tubes 15 are connected at their lower ends 60 through peripherally spaced fittings 50 in the wall 29 to the lower end of the water chamber 28, and are connected at their upper

ends in peripherally spaced relation to the upper end of the water chamber. Suitable plugs 51 are removably secured in the wall 30 at points directly opposite the fittings 50 to give access to the latter. Preferably, the 70 upper ends of the tubes 15 extend out of the heating chamber 14 through channels 52 formed in the upper end of the lower section 36 and between the sections 35 and 36, and open to the water chamber 28 through an overhanging peripheral wall 53 forming a continuation of the wall 30. The spacing between the tubes 15 in each coil gradually decreases from top to bottom in accordance with the tendency of the velocity of the products of combustion to decrease. As a result, the 75 velocity of the products of combustion is maintained more nearly constant.

Feed water or water returned from the heating system is adapted to enter the lower end of the water chamber 28 through an inlet pipe 54. Hot water or steam may be taken off from the upper end of a water chamber, and in the present instance the dome, through a plurality of take-off pipes 55.

When gaseous or vaporized fuel is used, a certain amount of leakage from the burners 16 may occur during idle periods. This leakage will collect in the combustion chamber 13, and unless removed may result in explosions when again starting up the heater. To prevent this, suitable means is provided for ventilating the combustion chamber 13. In the present instance, this means comprises an opening 56 through the center of the dome 12 and connected by a pipe 57 to the stack. Discharging downwardly in the opening 56 is an air nozzle 58 adapted to be connected to a suitable source of air under pressure, such as the line 18. The nozzle 58 serves to supply secondary air of combustion during the operation, and in so doing serves to prevent the fuel gases and the products of combustion from leaving the combustion chamber 13 through the opening 56. During idle periods 100 the supply of air to the nozzle 58 is cut off.

It will be evident that we have provided an advantageous water heater in which danger of explosions from gases collecting in the combustion chamber is avoided, in which the 115 water is heated quickly and has a rapid circulation, which is simple and inexpensive in construction and readily assembled and disassembled, and in which the walls of the combustion chamber are protected against overheating by means of a water jacket forming part of the circulatory system. By reason of the arrangement of the burners in peripherally spaced relation so as to direct the flames generally toward a common center, and the disposition of the air nozzle 58 to discharge a central downward stream of air, the flames are caused to be deflected downwardly toward the core 45, thereby causing the latter 120 to become intensely heated. As a result, the 125 130

inner coils 46 and 47 about the core 45 are heated approximately the same extent as the outer coils.

We claim as our invention:

- 5 1. A heater comprising, in combination, an upright cylindrical structure defining an internal heating chamber closed at the upper end by the dome, the peripheral walls of said structure and the walls of said dome defining a water chamber, a flue gas outlet at the lower end of said structure, a refractory core extending axially into the lower end of said structure, a series of heating tubes disposed in said heating chamber about said core and connected at spaced points to said water chamber, burner means in the upper end of said heating chamber, and means for ventilating the upper end of said heating chamber. 70
- 10 2. A heater comprising, in combination, a base constituting a flue gas outlet, a body structure on said base defining an upright heating chamber, the upper end of which constitutes a combustion chamber, a refractory core extending from said base centrally into the lower end of said heating chamber, a plurality of heating coils disposed in said heating chamber about said core, said coils being connected at opposite ends to said water chamber, a plurality of peripherally spaced burners opening to said combustion chamber, and means for ventilating said combustion chamber. 80
- 15 3. A heater comprising, in combination, a heating chamber, burner means in said chamber, means for supplying fuel to said burner means, means for supplying air to said burner means, a flue gas outlet for said chamber, means for ventilating said chamber, and means responsive to the supply of air to said burner means for rendering said ventilating means ineffective. 85
- 20 4. A heater comprising, in combination, a heating chamber, a central core in said chamber, burner means in one end of said chamber, and a series of concentrically arranged coils disposed about said core, the spacing between the turns in said coils decreasing progressively from said heating means toward the other end of said chamber. 90
- 25 5. A heater comprising, in combination, a hollow base having a flue gas outlet, and a stack connection communicating therewith, a cylindrical upright body structure on said base, said body structure comprising two concentrically spaced outer walls defining an annular peripheral water chamber, said body structure being sectioned vertically, a refractory core extending from said base centrally into the lower end of said body structure, a series of heating tubes coiled about said core, the lower ends of said tubes being connected to the lower end of said water chamber, the upper ends of said tubes extending outwardly between two of the sections of said structure and being connected to the upper end of said water chamber, a plurality of spaced heating 100
- 30 6. A heater comprising, in combination, an upright structure defining an internal heating chamber, said chamber having spaced peripheral walls defining a water chamber, a dome closing the upper end of said heating chamber, a flue gas outlet at the lower end of said heating chamber, a refractory core extending centrally into the lower end of said heating chamber, a series of heating tubes disposed in said chamber about said core and connected at spaced points to said water chamber, and heating means in the upper end of said heating chamber. 105
- 35 7. A heater, comprising, in combination, a base constituting a flue gas outlet, a body structure on said base defining an upright heating chamber opening to said base, the upper end of which constitutes a combustion chamber, a core extending from said base centrally into the lower end of said heating chamber, a plurality of heating tubes disposed in said heating chamber about said core, said tubes being connected at opposite ends to said water chamber, and a burner opening to said combustion chamber. 110
- 40 8. A heater comprising, in combination, a heating chamber, burner means in said chamber, a flue gas outlet for said chamber, exhaust means opening from said chamber for ventilating said chamber, and a means for directing a stream of pressure fluid from said exhaust means into said chamber to prevent the exit of gases through said exhaust means. 115
- 45 9. A heater comprising, in combination, a heating chamber, burner means in one end of said chamber, a series of concentrically arranged tube coils disposed in the other end of said chamber, the spacing between the turns in said coils decreasing progressively from said heating means toward said other end of said chamber, and means for withdrawing flue gases from said other end of said chamber. 120
- 50 10. A heater comprising, in combination, a hollow base having a flue gas outlet, an upright body structure on said base, said body structure comprising two spaced outer walls defining a peripheral water chamber, said body structure being sectioned vertically, a series of heating tubes in said structure, the lower ends of said tubes being connected to the lower end of said water chamber, the upper ends of said tubes extending outwardly between two of the sections of said structure and being connected to the upper end of said water chamber, a plurality of spaced heating 125
- 55 65 110 115 120 125 130

means disposed in the upper section, means for supplying water to said water chamber, means for taking off water from said water chamber, a draft outlet for ventilating said upper section and pressure fluid discharge means in said outlet adapted when operated to prevent the discharge of gas through said outlet.

5 In testimony whereof we have hereunto affixed our signatures.
